UNITED STATES PATENT OFFICE.

AARON LANCASTER, OF PRINCETON, IOWA.

WIND-MOTOR.

SPECIFICATION forming part of Letters Patent No. 523,217, dated July 17, 1894.

Application filed January 11, 1894. Serial No. 496,499. (No model.)

To all whom it may concern:

Be it known that I, AARON LANCASTER, of Princeton, Scott county, and State of Iowa, have invented certain new and useful Improvements in Wind-Motors, of which the following is a full, clear, and exact description, reference being had to the accompanying drawings, forming a part hereof.

My invention relates to an improved wind-
motor, and consists in the novel arrangement,
combination and construction of parts as will
be more fully hereinafter described and des-
ignated in the claims.

In the drawings: Figure 1 is a side eleva-
tion of my improved motor, showing it
mounted on a power as required for practical
use. Fig. 2 is a horizontal cross section taken
on the line 2—2 of Fig. 1. Fig. 3 is a vertical cen-
tral section of Fig. 1, parts of the same being
removed. Fig. 4 is a horizontal cross section
taken on the line 4—4 of Fig. 3. Fig. 5 is an
enlarged detail perspective view more clearly
showing how the vane is connected to its sup-
port.

1 indicates a tower and 2 a platform upon
which the motor is supported.

3 indicates a vertical shaft which is square
adjacent its upper end and its extreme upper
end is round so as to freely work in bearings.

30 Connected to the upper side of the platform
2 and at each corner is a bar 4 which extends
upward to the top of the motor and then in-
wardly and are connected to a disk 5 which
forms bearings for the upper end of the
shaft 3.

35 The platform 2 is provided with an open-
ing 6 in its center, from which four radial
slots 7 project, thus forming projections 8 in
the platform. Connected to the inner corners
40 of the projections 8 are four vertical supports
9 and 10 which extend upward a suitable dis-
tance to support a disk 11. Located on the
disk 11 is another disk 12 the same in con-
struction as the disk 11. Formed in the ad-
45 jacent sides of the disks 11 and 12 is an an-
nular groove 13 to form a guide-way for an-
tifriction balls 14. Connected to the periph-
eral edge of the disk 12 and extending up-
wardly a suitable distance, is a casing 15
50 which is constructed with a cover 16. By this
construction it forms a chamber 17 therein;

one side of said casing is cut away for the
purpose hereinafter mentioned.

Mounted on the square portion of the shaft
3 and in the chamber 17 is a casting 18 to 55
which a series of radial blades 19 are con-
nected, which are of such a size that they will
readily rotate in said chamber.

Connected to the cover 16 of the casing 15
and extending downward therefrom, adjacent 60
one corner of the cut away portion, is a vane
20 for the purpose of holding the cut-away
portion in alignment with the wind. (See
Fig. 2 for illustration.)

21 indicates another casing, which is con- 65
structed of a suitable size that it will slide
over the casing 15, the upper end of which is
open to allow this operation, and the lower
end is constructed with an inwardly project-
ing annular flange 22 to which a suitable 70
number of bars 23 are connected, and their
opposite ends being connected to a sleeve 24
which is located on the vertical shaft 3.

25 indicates a rope which is connected to
the lower end of the sleeve 24 and extends 75
upward and passes over a pulley 26 connected
to the adjacent side of the support 9 and
thence downward to any suitable point.

The vane 20 is constructed with a bar 27
connected to its upper end and a bar 28 con- 80
nected to its edge adjacent the casing, which
is bent at right angles adjacent its top and is
parallel with and engages the bar 27, they ex-
tending outwardly a suitable distance from
the corner of said vane to be detachably in- 85
serted in a plate 29 which is connected to the
cover 16 and these bars are held in position
by a bolt 30 passing through said blade and
the adjacent ends of the bars 27 and 28.

The operation is as follows: When the mo- 90
tor is in the position as shown in Figs. 1 and
2 and the wind is coming from the direction
indicated by the arrow in Fig. 2, it will strike
the blades 19, which project out of the cut
away portion of the casing 15, this cut-away 95
portion allowing the wind to come in contact
with the blades at one side of the shaft only.
When the wind so strikes said blades it will
carry them around and they being connected
to the shaft as hereinbefore stated will cause 100
said shaft to be rotated, the vane 20 holding
the casing in the required position. When

it is desired to stop the operation of the motor, the operator draws down on the rope 25 which will cause the casing 21 to telescope the casing 15, thus closing the cut-away portion, which will cut off the wind from the blade thus causing the motor to stop.

What I claim is—

1. In a wind motor of the class described, a disk mounted on suitable supports, another disk revolubly mounted on the first mentioned disk, an upwardly projecting casing a portion of which is cut away connected to the last mentioned disk, a vertical shaft passing through the center of said disk and the casing, a series of radial blades located in the chamber formed by said casing and connected to said shaft, and means for opening and clos-

ing the cut-away portion of said casing, by the telescoping of the casings substantially as herein specified.

2. In a wind motor, a vane constructed with a bar connected to one edge the upper end bent at right angles thereto, a bar connected to the upper end of said vane which projects outwardly adjacent to and parallel with the upper end of the first mentioned bar, substantially as set forth.

In testimony whereof I affix my signature in presence of two witnesses

AARON LANCASTER.
